UNITED STATES PATENT OFFICE.

ELMER R. CORWIN, OF CHICAGO, ILLINOIS, ASSIGNOR TO MONARCH TELEPHONE MANUFACTURING COMPANY, OF CHICAGO, ILLINOIS, A CORPORATION OF ILLINOIS.

TELEPHONE-EXCHANGE SYSTEM.

No. 902,715.

Specification of Letters Patent.

Patented Nov. 3, 1908.

Application filed December 12, 1904. Serial No. 236,593.

To all whom it may concern:

Be it known that I, ELMER R. CORWIN, a citizen of the United States of America, and a resident of Chicago, county of Cook, and 5 State of Illinois, have invented a new and useful Improvement in a Telephone - Exchange System, of which the following is a specification.

My invention relates to that class of telephone exchange systems in which a central source, or central sources, of energy supplies the lines with current for the operation of the signals, and, if desired, for the operation of the transmitters as well, and has for its general object the simplification of the wiring of the central office switchboard by limiting the number of conductors required to be carried through the multiple jacks to the otherwise necessary pair of limbs of the line, and also 20 has as an object a similar limiting of the flexible cords to a single pair without auxiliary signal strands, with the attendant advantage of requiring but two conductors to appear in the plug for registry with a similar 25 number of electrical parts in each of the jacks. The advantages of this economizing in the parts of the structure of the switchboard and the consequent investment, and those of increased economy in maintenance, 30 and of the more limited number of cord and plug conductors to be maintained, are well known to those skilled in the art. In my invention these advantages are gained, together with those of reliability of signals and 35 the preservation of an electrical balance of the line.

My invention is illustrated in the accompanying drawing, which shows the circuits of a cord circuit and operator's telephone circuit, and two line circuits adapted to be connected together by cord circuits of the type shown.

Referring to the drawing, 1 and 2 are the substation telephones of two of the lines; 45 these may be of any type suitable for use with a system having signals operated on the central energy plan, the important requirements being that when the receiver at the station is on its hook, the circuit of the instrument is opened to direct current, although closed to alternating current for the operation of the signal bell. If there be no necessity of a signal bell, as is true in equipments for outgoing service only, the circuits of the 50 telephone may be truly open to all currents

except in times of use. When the receiver is not on the hook, a path for direct current is provided through the instrument. If the system is to be adapted for a central energy supply of current for the transmitters at the 60 substations, no local battery will be required although such a substation circuit as would use a local battery might be adapted for use with my system without sacrificing any of the advantages of automatic control of central office signals.

3 and 4 are the limbs of one of the lines, and 3^a and 4^a, those of the other. As the two lines illustrated are quite identical, first particular reference will be made in this description to that which is shown at the left of the sheet. It is this line which is considered as originating a call, and the other as receiving a call. The parts 5 and 6, 5^a and 6^a, respectively, compose two of the spring jacks 70 associated with the line formed of the limbs, 3 and 4. The parts 5 and 5^a, respectively, are the test bushings usual in spring jacks, and are adapted to make contact with the sleeves, as 7, of such plugs as are indicated as 80 a whole by 9. The tip, 8, of such plug will register with the spring, 6, of a jack. The relay, 10, is permanently connected to the limb, 3, of the line, and the other terminal of its winding to the live pole of the battery, B. 85 If the subscriber at station, I, removes his telephone from its hook, current will flow from the battery, B, through the relay, 10, over the limb, 3, of the line, through the telephone instrument, to the central office over 90 the limb, 4, of the line, through the contact between the armature, 11, and the back contact, 12, of the relay, 13, and thus to ground. The result will be the actuation of the armature, 14, of the relay, 10, making contact, 15. 95 As the armature, 16, of the relay, 13, is upon its back contact, 17, current will now flow from the battery, B, through these contacts and the lamp, 18, to ground. The lamp, 18, being adapted to give a visible signal at the 100 potential of the battery, B, it will now do so, notifying the operator that a call upon the line in question requires to be answered, and the lamp, 18, will remain so displaying a signal until the call is answered, or until the subscriber has returned his receiver to its hook. 105 Upon the answering of the signal by the insertion of the plug, 9, in, say, the jack formed of parts 5 and 6, current will flow from the battery, B, through the relay, 13, over the 110

wire, 19, by contact of the test bushing, 5, to the sleeve, 7, of the plug, 9, then through the winding of the relay, 20, to ground. But the winding of the relay, 20, is of turns and resistance relatively few and low with relation to those composing the winding of the relay, 13; it is a consequence that the current which flows through these relays, 13 and 20, in series, is ample to energize the former, 10 moving both its armatures, 11 and 16, but not moving the armature, 21, of the relay, 20. Four results, one passive and three active, come from these conditions:

First: The circuit of the lamp, 18, is interrupted by breaking of contact between the armature, 16, and its point, 17, thus effacing the signal as is necessary.

Second: The making of contact between the armature, 11, and its point, 22, connects 20 the test bushings, 5 and 5^a, through conductor, 19, with the limb, 4, of the line. It will be observed that this condition with reference to the limb, 4, has not before existed, nor have the test bushings been before connected to that limb of the line except over 25 another and longer path.

Third: As the armature, 21, of the relay, 20, is not moved, the supervisory signal lamp, 23, has its circuit left open which 30 leaves the lamp in condition of darkness, to indicate to the operator that the subscriber is at his telephone.

Fourth: Whereas the test bushings, 5 and 5^a, had during a time of no connection of a 35 plug with one of them, a potential with reference to the earth quite the same as that of the live pole of the battery, there is now such a potential with reference to the earth at these test bushings as is controlled by the 40 drop of potential through the winding of the relay, 20; and this change of the electrical condition of the test bushings 5 and 5^a, and such others as may be connected with the line in question, may enable a busy test to be 45 made on the line if occasion shall require.

Actuating the listening key designated as a whole, 24, the operator connects her telephone circuit with the limbs of the cord circuit, and therefore with the limbs of the line. 50 The operator's telephone circuit is quite as usual except with reference to the winding, 25, the spring, 26, and the contact, 27, all of which have to do with busy test functions, and will be described later. Having learned 55 from the calling subscriber what line it is that he desires, the plug designated as a whole, 28, (being the plug of the pair particularly intended for calling,) will be selected by the operator, and its tip, 29, 60 touched against the test bushing of the called line. Either a click will be heard, indicating that that line is in use, or none will be heard, indicating that it is free. The latter will be true and the line may be taken if the test 65 bushings have the same potential as the live

pole of the battery, which in turn will be true unless some plug, electrically similar in circuit to plugs, 9 and 28, is in a jack of that line. If the latter is true, the test potential of the bushings will be somewhat less than 70 that of the live pole of the battery, and a click will be received by the operator for the following reason:

The tip, 29, of the plug with which the test is made has a circuit through the ringing key, 31, of usual and standard type, directly to the contact, 27. This is individual to the particular listening key of the cord circuit in use. As the listening key, 24, is still actuated since receiving the called number from 80 the calling subscriber, the spring, 26, will be in contact with the point, 27. Other listening keys of the group of cord circuits used by the operator, have similar springs to 26, and these springs of a given operator's equipment are all connected together and to one of the terminals of the winding, 25, of an induction coil associated with the operator's telephone. The other terminal of that winding, which is neither the usual primary 85 nor secondary winding, but which we may call the tertiary winding, is connected to the live pole of the battery, B. This tertiary circuit is of quite high resistance. At the 90 time of its contact, therefore, current will flow from the battery, B, through the winding, 25, and contact of spring, 26, with point, 27, through the ringing key, 31, to the tip, 29; and if there is a connection of some other 95 plug with another jack of that line, current will flow over the test bushing touched, as for example, 32, and over the wire, 33, to that test bushing of the busy line in which exists the plug which is making the line busy. This may be considered to be 34. From 100 this point, as 34, current will further flow to the sleeve of that distant plug, through the distant ringing key similar to 31, through the distant supervisory relay of that distant cord circuit similar to 35, and thus to ground. 105 As current is still flowing through that distant relay, similar to 35, there will be a potential somewhat less than that of the live pole of the battery, and the current impulses 110 thus resulting by induction in the secondary winding of the induction coil of the testing operator's telephone set, will produce the necessary click in the operator's receiver.

Assuming that no click is heard, and that the line is taken by the operator, a registry of contacts similar to that described with reference to the calling subscriber's line will enable ringing current to pass from the generator, 36, and the tip, 29, of the plug, 28, to the wire, 3^a, of the line, through the ringer, 37, and the condenser, 38, of the telephone, 2, to the central office over the limb, 4^a, and to ground by contact of the armature, 39, with the point, 40.

So long as the ringing of the subscriber's 130

bell does not result in his response, the relay, 41, will not be energized, and its armature, 42, and point, 43, will establish a circuit which will be seen to shunt the winding of the relay, 44, by the mere resistance of the connecting wires; the relay, 44, is thus prevented from operating, which it would do in series with the supervisory relay, 35, of the circuit if it were not for this short circuiting. 5 The relay, 35, is therefore in series with but negligible resistance and the battery, B. As it is similar to the relay, 20, described as having few turns and low resistance, the relay, 35, will be energized under these conditions 10 in a sufficient degree to operate and will close its armature, 45, upon the contact, 46. This in turn will place the lamp, 47, in shunt with the winding of the relay, 35, in which condition, with a practical proportion of 15 values which I will describe later, the lamp, 47, will be illuminated. The signal thus given is of the meaning to the operator that the subscriber being called has not replied, and she will either continue to ring his bell, 20 or will in time notify the calling subscriber 25 that he does not respond.

When the called subscriber does respond, the relay, 41, is energized quite as was true with the relay, 10, in the described originating call. The breaking of contact between 30 42 and 43, not only so far decreases the current through the relay, 35, in such a degree as to cause its armature to fall away, extinguishing the lamp, 47, but by the operation 35 of the relay, 44, extends the limb, 4², of the called line through the armature, 39, and the contact, 48, to the conductor, 33, the bushing, 32, and the sleeve, 30, of the calling plug, 28. Conversation may now ensue. 40 But for the breaking of contact between the other armature, 49, and its point, 50, the line lamp, 51, of the calling line, would have been lighted, which would have given a signal, falsely indicating an originating call. 45 This will not occur, and for the reasons stated. As the relays, 20 and 35, during the progress of conversation, are receiving insufficient current to operate, their associated lamps will remain dark. Upon the completion 50 of the conversation and the hanging up of the telephone receivers by both of the subscribers, or by either of them, the corresponding relay, 10 or 41, will allow its armature to be released. This will restore contacts which I have described before, shunting the windings of the relays, 13 or 44, increasing 55 the current through the corresponding supervisory relay, 20, or 35, bringing the associated lamp, 23 or 47, again into action, 60 indicating that the connection requires attention, this being the withdrawal of both plugs if both lamps are illuminated. So far as the signals are concerned, their behavior is quite as is common in general practice at 65 this time.

In order that the consequences of operations may be as I have described, I find that in practice the resistances of the various relays and signals which are likely to have inter-relations are practical when they are 70 about as follows: If the potential of the battery, B, is approximately 40 volts, the relay, 13, may have a resistance of 2000 ohms, and the relay, 20, of about 200 ohms, accomplishing the result of operating or not operating 75 as I have described. These are merely suggested practical values; as, due to the mechanical and magnetic dimensions of the supervisory relays, considerable variation may be made from the values I have assigned 80 without at all effecting the results to be achieved. As the supervisory lamps are only placed in shunt with their controlling relays at a time when the entire resistance of the relays, 13 and 44, is shunted, the drop of 85 potential across the lamp terminals is therefore the entire voltage of the battery, or very near to that. With a 40 volt source of energy, therefore, 40 volt lamps are practical for supervisory purposes. 90

During conversation, current is supplied to the subscriber's telephone through the line relay and supervisory relay, each in series with one of the line conductors. These relays, in the case of the line to the station, I, 95 in the drawing, would be respectively those designated as 10 and 20. It will be remembered that during actual conversation, the relay, 20, is not energized by sufficient current to draw up its armature, 21, and therefore the inductance of that part of the circuit is not diminished by the non-inductive shunt constituted by the lamp, 23. 100

The condensers, 54 and 55, serve the purpose of transmitting voice currents with ease, 105 and at the same time preventing false signals due to the operation of the supervisory signal associated with the answering cord by any motions of the hook of the telephone on the called line. Individuality of signals is 110 thus retained.

It will be seen that the operation of the supervisory signal lamps, 23 and 47, depends, with the particular arrangement which I have shown, upon the existence of a path for current through the lamp, as well as upon the presence of a sufficiently low resistance in series with the lamp to enable it to secure sufficient current. For instance, in the case of the lamp, 23, associated with the answering cord, if the contact of the armature, 21, with the relay, 20, were not made upon its point, there would be no circuit for current through the lamp, 23. But if this contact were made and by accident or design remained closed, the supervisory signal would still be operative and responsive to the necessary motions of the hook switch at the calling subscriber's station; and this is for the reason that when the subscriber's telephone 115 120 125 130

receiver is upon the hook, the contact of the armature, 14, with its normal point, is not broken, and the resistance of the relay, 13, is effectively shunted from being in series with the lamp, 23. If the subscriber's receiver were off the hook, the relay, 10, would be energized and the contact shunting the relay, 13, would be broken. So great a resistance as I have assigned to the relay, 13, would effectively prevent the glowing of the lamp, 23, if the latter is adapted to give a practical signal on the full voltage of the battery. I desire, therefore, to have this explanation of my invention understood to point out that with proper and feasible proportion of parts, the supervisory signal system may be made operative on either of the plans which I have described as involving the relations of the supervisory lamp, 23, the circuits by which it is controlled, and in which it operates.

I do not wish to be limited to the use of supervisory relays in practicing all features of my invention.

Having thus described my invention, what I claim as new and desire to secure by Letters Patent is,

1. In a telephone system, a telephone line, a source of current, a relay permanently in series with said source of current and one limb of said line, two-conductor spring jacks having one conductor of each permanently connected to the limb of said line containing said relay and the other conductor of each normally disconnected from the remaining limb of said line, a relay adapted when energized to connect the remaining limb of said line to the conductors of said spring jacks not normally connected to that line, a signal lamp adapted to be operated by the operation of said series relay, and a shunt path about the other said relay adapted to be broken when said series relay is energized, substantially as described.

2. In a telephone system, a line of two limbs, a spring jack of two members, a conductor permanently connected between one limb of said line and one member of said spring jack, a cut-off relay, a line relay, line relay contacts normally shunting said cut-off relay, and means adapted to break the shunt from said cut-off relay and to connect the other limb of said line immediately to said spring jack during conversation over said line, substantially as described.

3. In a telephone system, a telephone line of two limbs, a spring jack of two conductors, a cord circuit of two strands, a line relay normally in series with one limb of said line, a cut-off relay normally short circuited by contacts of said line relay, a source of current having one pole permanently connected to both said relays, supervisory relays permanently in bridge between one strand of said cord circuit and the other pole of said source of current, and means adapted to

place said cut-off relay and one of said supervisory relays in series with each other and the source of current without operating said supervisory relay, substantially as described.

4. In a telephone line, a source of current, a line relay, a cut-off relay normally short circuited by contacts of said line relay, a two-strand cord circuit, a supervisory relay bridged between one strand of said cord circuit and one pole of said source of current, 70 spring jacks connected to said telephone line, plugs connected to said cord circuit, means adapted by a connection of one of said plugs with one of said spring jacks to operate the armature of a corresponding one 80 of said supervisory relays while the short circuit of said cut-off relay continues, and to release it when the short circuit is broken, and means adapted to energize said cut-off relay when the short circuit is broken, substantially as described.

5. In a telephone system, a source of current, a supervisory relay having one winding and adapted not to attract its armature during conversation, said source and said winding being in series with each other and with the line limbs and sub-station telephone; a supervisory lamp in a circuit normally open, and line controlled means adapted to place said lamp in shunt with said relay when said 95 relay is energized to attract its armature, substantially as described.

6. In a telephone system, a source of current, a two-strand-cord circuit, a supervisory relay having one winding, said source and 100 said winding being in series with each other and with the line limbs and sub-station telephone; a supervisory lamp in a circuit normally open, line controlled means adapted to place said lamp in shunt with said relay when 105 said relay is energized, and means adapted not to energize said relay when the receiver of a connected sub-station telephone is off the hook and to energize said relay when the receiver of a connected substation telephone 110 is on the hook, substantially as described.

7. In a telephone system, a source of current, a supervisory relay adapted not to attract its armature during conversation, a supervisory lamp, line controlled means adapted to place said supervisory lamp in shunt with said relay when said relay is energized, and a circuit including said source of current, said relay, the limbs of a connected telephone line and a substation telephone and 115 adapted to furnish to the substation telephone energy for speech transmission, substantially as described.

8. In a telephone system, a source of current, a supervisory relay having a single 125 winding, a supervisory lamp placed in shunt with the winding of said relay by the contacts of said relay when said relay is energized, a substation telephone having a hook switch, a circuit closed during conversation 130

including said source of current, said relay and said hook switch, and line controlled means whereby said relay is energized while said hook switch is open and deenergized 5 while said hook switch is closed, substantially as described.

9. In a telephone system, a source of current, a supervisory relay, a supervisory lamp in a circuit normally open, means adapted to 10 place said lamp in shunt with said relay when said relay is energized, said lamp and

relay in shunt then being in series with jack and line relay contacts severable by disconnection of the plug from the jack.

Signed by me at Chicago, county of Cook, 15 State of Illinois, in the presence of two witnesses.
